UNITED STATES PATENT OFFICE.

NEAL W. PLOOSTER, OF MINNEAPOLIS, MINNESOTA.

DESIGN FOR A TOY DOG.

Application filed August 6, 1926. Serial No. 18,625. Term of patent 7 years.

To all whom it may concern:

Be it known that I, NEAL W. PLOOSTER, a citizen of the United States, residing at Minneapolis, in the county of Hennepin and State of Minnesota, have invented a new, original, and ornamental Design for a Toy Dog, of which the following is a specification, reference being had to the accompanying drawing, forming part thereof.

Fig. 1 is a side elevation of the article showing my new design;

Fig. 2 is a front elevation of the article showing my new design; and

Fig. 3 is a top view of the article showing my new design.

I claim:

The ornamental design for a toy dog, as shown.

NEAL W. PLOOSTER.
